UNITED STATES PATENT OFFICE.

JULIUS GLUCK, OF NEW YORK, N. Y., ASSIGNOR TO AMERICAN TAXIMETER COMPANY, OF NEW YORK, N. Y., A CORPORATION OF NEW YORK.

PRINTING UNIT FOR TAXIMETERS.

Application filed October 14, 1920. Serial No. 416,901.

To all whom it may concern:

Be it known that I, JULIUS GLUCK, citizen of Hungary, residing at New York, in the county of New York and State of New York, have invented certain new and useful Improvements in Printing Units for Taximeters, of which the following is a specification.

This invention relates to printing devices particularly adapted to use in connection with taximeters.

A primary object of the invention is to provide a simple and compact printing unit having a novel and distinctive impression mechanism including a plurality of devices that operate with a snap action as distinguished from a slow moving presser bar heretofore employed. In this connection the invention contemplates the provision of a plurality of relatively independent impression elements for the individual fare types which are susceptible of being operated in successive order to progressively take off an impression from the series fare types instead of accomplishing this operation instantaneously as in the case of a common or universal presser bar which engages all of the fare types at once upon reaching the limit of its travel.

Another object of the invention is to provide a simple and compact unit which may be readily detachably positioned over the fare types to provide in effect a cover or hood therefor, and which may be coupled and uncoupled with its actuating means by the act of taking out and replacing.

A further object is to provide a printing unit, which although controlled by the flag of the meter is not dependent upon the same for its operation, but employs a separate and independent operating key having means for cooperating with the flag to prevent movement of the latter during certain stages of the operation of the printing device, while on the other hand the flag performs a similar locking function in connection with the printing mechanism.

With the above and other objects in view which will more readily appear as the nature of the invention is better understood,

reference may be had to the accompanying drawings, in which:

Figure 1 is a top plan view of the printing unit without the cover.

Figure 2 is a vertical cross-sectional view thereof with the cover in place.

Figure 3 is a detail view of one of the impression hammers in striking engagement with the type on one of the type wheels.

Figure 4 is a detail plan view of the cam operating shaft for the impression hammers.

Figure 5 is a side elevation of the printing unit, with the cover removed, and showing its relation to the printing key and flag.

Figure 6 is a side elevation of the opposite end of the unit shown in Figure 3.

Figure 7 is a top plan view of the printing unit with the cover thereof in place.

Figure 8 is an enlarged detail view of the clutch device for enabling the tape feeding roll to be operated manually instead of automatically.

Figure 9 is a rear elevation of the back of a meter on which the printing unit may be installed showing the relative location of the printing key to the flag, the latter being in its first or "vacant" position.

Figure 10 is an enlarged elevation of the portion of the meter shown in Figure 9, viewing the same from the opposite side shown in that figure, to more clearly illustrate the printing unit actuating means and the several positions of the flag.

Figures 11, 12, 13, 14, 15 and 16 are diagrammatic views showing the relative positions of the wheel carried by the printing key shaft and the check wheel carried by the flag shaft, during the movement of the flag from one position to another, and also during the operation of the printing key.

Similar reference numerals designate corresponding parts throughout the several figures of the drawings.

The printing mechanism contemplated by the present invention is of such a character that it may be conveniently handled as a separate unit without disturbing the meter casing parts or in any way interfering with the operating mechanism thereof. To this end, it will be observed from the drawings

that this printing unit may include a suitable platform or a base plate 1 carrying at its under side the depending lugs 2 for facilitating the positioning of the same on the meter casing, while its upper side carries the vertically disposed side walls 3 and 4 for supporting and carrying many of the various instrumentalities included in the organization of the printing unit.

- 10 The said side wall 3 is preferably provided with suitable bearings 5 and 6 for receiving the main drive shaft 7 of the printing unit. This shaft is provided at one end with a transverse key 8 for engaging in the slot 9 of the hub portion 10 of the gear 11 forming a part of the printing unit actuating gear train to be presently referred to. The said gear 11 as well as its associated gear train is carried by the back wall 12 of the meter and the key 8, on the shaft 7, therefore, constitutes an effective coupling between the printing unit actuating mechanism and the main drive shaft of the unit when engaged with the slot 9 referred to.
- 15 20 25 30 35 40 45 50 55 60 65 As the slot 9 opens at the end as well as the periphery of the hub 10 it will be apparent that the key 8 may be readily inserted and withdrawn as the printing unit is placed into or removed from its position on the top of the meter casing. The end of the shaft 7 opposite the key 8 is provided with a worm pinion 13 meshing with a similar pinion 14 carried by one end of a novel cam shaft 15. This cam shaft 15 constitutes one of the novel and distinctive features of the invention, and as will be apparent from Figure 1, readily provides for the actuation of an individual impression element for each printing wheel independently of the other. That is to say, this shaft has thereon a plurality of spaced individual cam disks 16 having portions of their peripheries 17 cut away as at 18 with said cut away portions progressively set in such a manner that as the said shaft rotates it will progressively release a plurality of impression hammers for taking the impressions from the fare type wheels actuated by the meter mechanism, and then raise the hammers again. The mutilated or cut away portions 18 of the cams are sufficient to give ample clearance for the relatively free ends 19 of the hammers 20 of each individual impression element, when the main operating shaft 7 turns the cam shaft 15 through the gears 13 and 14 during the manipulation of the printing key K, the free ends 19 of the impression hammers will drop from the edge of the cam recess 18 in the disk and by reason of the clearance provided thereby have a free and unobstructed path of movement toward the printing types T, whereby the impression stud 23 carried by each hammer may press the paper and inked ribbon together over the type and take the desired impression.

The bar 22 which carries all of the springs 21 of the impression hammers is mounted in the side walls 3 and 4 of the frame by means of the fastenings 24 or their equivalent which permits of the adjustment of the impression hammers with reference to the axis constituted by the fastenings 24 whereby the hammers may be pressed with greater or less force against the peripheries 17 of the individual cams to insure the impression studs 23 striking the fare types with the required impact desired. To effect this adjustment as well as prevent retrograde creeping of the bar about the relatively pivotal supports 24, the said bar is provided with an arm 25 adapted to be engaged by a set screw 26 carried in the ear 27 of the side wall 4. As shown in Figure 2 of the drawings the said set screw 26 is exposed through the opening 28 in the casing or cover C so that the position of the arm and hence the tension of the springs 21 may be readily adjusted even when the cover is in position.

From the foregoing it will be apparent that the printing mechanism includes in its organization a rotatable actuating element in the form of the shaft 15 carrying thereon a plurality of spaced operating elements for the individual striking hammers for each type printing wheel. Normally, the free ends 19 of the impression hammers rest upon the circular peripheral portions 17 of the cam disks, but when the flag F of the meter is in position to permit the manipulation of the printing key K, the movement of the latter will actuate intervening mechanism to cause the rotation of the shaft 15 which will bring the cam slots 18 into position to clear the ends of the hammers 19 and permit them to fall under the influence of the relatively stiff springs 21, whereby the impression studs 23 of the hammers will strike the paper and inked ribbon together over the type with a sharp quick blow. By reason of the progressive setting of the cam disks 16 on the shaft, the impression hammers will be progressively released from the circular peripheries of the cam disks to fall through the clearance of each disk to permit the hammers to successively drop. (See Figure 3.) Upon the further rotation of the printing key to complete the printing operation the shaft 15 will obviously be rotated further to thereby shift the cam slots 18 and again lift the ends 19 of the hammers 20 to the position shown in Figure 2.

Paper or tape feeding means.

The paper or tape for receiving the impression from the fare type wheels W is preferably carried on a roll A journaled in the arms 3^a and 4^a and projecting rearwardly from the side walls 3 and 4. It will of course be understood that the rolls or

reels A are removable and renewable, and when positioned for use, the portion of the tape to be used for the printing operation preferably passes beneath the lower edge of 5 the cover C and through the guide G pivotally supported as at G' in the opposite side walls 3 and 4 of the frame and extending throughout the width of the unit. This 10 guide G has its discharge end located adjacent the clearance provided by the spaced printing wheel hoods or guards G² and G³ carried by the upper side of the base plate 1, and after the paper passes through the 15 guide and across the clearance it is threaded between the feed rolls R and R', the former being the master feed roll which is rotated by the cam shaft 15 and the latter being simply an idler. The said idler roll is yieldingly supported in the arms R² pivoted as at 20 R³ and held under tension by the springs R⁴, a set of said arms and springs being provided at each end of the said roll R' as will be apparent from Figures 3 and 4. Obviously, the relatively swinging mounting 25 of the idler roll R' and the spring means for tensioning the same will cause the periphery thereof to firmly engage with the periphery of the positively driven or rotated feed roll R which is preferably surfaced 30 with rubber or the like.

The paper or tape feeding mechanism above referred to is controlled automatically by the movement of the cam shaft 15. That is to say, the end of said shaft which is journaled in the wall 4 carries a disk 30 having a single tooth 31 (see Figure 6) for engaging with a Geneva gear 32 loosely supported on the shaft 33 of the paper feed roll R. The hub portion 35 of the said Geneva gear 36 is provided with a clutch portion for engaging with the mating clutch portion of the spring pressed clutch element 36 keyed to the shaft 33. (See Fig. 8.) At the extremity of the shaft 33 is provided a relatively large wheel 37, and between this wheel and the clutch element 36 is a spring 38 for yieldingly maintaining the said clutch member 36 in engagement with the hub 35 of the Geneva gear. With this arrangement it 45 will be apparent that when the printing key K is moved through the first half of its cycle the cam shaft 15 will be rotated in the direction of the arrow in Figure 6 to release the hammers and again raise them, but during the second half of the cycle of the printing key the hammers will ride on the peripheries of the cams as the shaft 15 continues to rotate to cause the single tooth 31 of the wheel 30 to engage the Geneva gear 40 on the shaft 33 of the feed roll R and thus rotate the latter a sufficient distance to move the tape T whereby the impression made thereon by the action of the printing hammers will be moved out of the zone of the 45 next print. This is then repeated in all sub-

sequent printings. At the end of the taxi-cab's operating period, the wheel 37 is manually operated so that the portion of the paper on which the last print was made is brought through the slot S. A means is 70 then provided for tearing off this portion of the tape and the mechanism is then ready for further operation.

When the wheel 37 is manipulated manually it will be apparent that the teeth of the 75 clutch element 36 will simply slide over the clutch teeth on the hub 36, and that the Geneva gear will not be rotated by reason of the fact that the concave portion 32^a of one of its teeth is in engagement with the periphery 31^a of the wheel 31.

From the foregoing it will be apparent that the rotation of the cam shaft 15 automatically effects the feeding of the paper across the zone of the fare-type wheels W by 85 reason of the Geneva gear and clutch arrangement connecting the end of the shaft 15 with the shaft 33 carrying the roll R. Or, on the other hand if it is desired to facilitate the passage of the tape through the 90 printing unit this can be done manually through the rotation of the wheel 37.

Inked ribbon feed.

The means for feeding the inked ribbon 95 across the clearance provided by the guards G² and G³, and next to the printing types of the wheels W is preferably controlled directly by the main driving shaft 7, as will presently appear. By reference to Figure 100 2 it will be seen that the spool 40 for carrying the inked ribbon is supported in the depending ears 41, and the inked ribbon 42 carried thereby is led across the clearance between the type guards referred to, and 105 onto the winding spool 43 located at the rear of the unit, and, supported in the depending ears 44 of the base plate 1.

The winding spool 43 is rotated directly 110 by the main drive shaft 7 as heretofore indicated, and to this end there is provided a shaft 45 journaled in a bearing stirrup 46 depending from the plate 1, the said shaft having a detachable engagement with one end of the spool 43 and also carrying a gear 47 (Figure 4) for engaging with a worm 48 on the shaft 7. When the said shaft 7 rotates through the manipulation of the printing key K the worm 48 will 115 rotate the gear 47 and thus rotate the spool 43 to bring a fresh portion of the inked ribbon across the type of the fare printing wheels. In the arrangement shown the feed of the ribbon is opposite to that of the tape which has the advantage of preventing the creeping of the tape during the 120 feed of the ribbon.

Actuating mechanism for printing unit.

As pointed out in connection with the 130

description of the shaft 7 and its key or cross pin 8, the gear 11 of the actuating gear train is carried by the back plate 12 of the meter. This gear 11 meshes with an 5 idler gear 11^a which in turn meshes with the idler 11^b both of which are also mounted on the back 12 of the meter and cooperate to transmit motion to the driving gear 11 from the gear 50 carried by the shaft 51 10 on which the key K is mounted.

The said key shaft 51 is, therefore, the operating shaft for the train of gears leading to the gear 11, and in order to prevent the manipulation of the key K and the actuation of this gear train except at proper intervals in the operation of the meter, the said shaft 51 carries therewith a suitable check device which cooperates directly with the flag F. In addition to the check means 15 that cooperates directly with the flag the shaft 51 carries a ratchet wheel 52 whose check teeth 53 are engaged by a spring pressed pawl 54 for preventing backward rotation of the shaft 51.

20 The check means above referred to as cooperating with the flag is preferably a disk 55 whose purpose is to limit the turning of the shaft 51 for a greater distance forward than will be required to effect the proper operation of the printing mechanism, and also provide means for holding the flag in printing position to prevent tampering with the totals registered by the printing wheel, while the printing key is 25 being operated.

When the flag F is in vacant position, the full line position in Figure 10, disk 55 is locked and consequently the shaft 51 can 40 not be moved to manipulate the gear train leading to the printing unit.

On the other hand, when the flag F and key K are in the positions above stated the elements associated with the flag F which 45 cooperate with the disk 55 are free to permit the movement of the flag from the full line or vacant position shown in Figure 1 to the first or second tariff positions F¹ and F² respectively, as well as to the not-recording position F³ and the printing position F⁴. When the flag is in either of the positions, F¹, F², or F³ the disk 55 still 50 remains locked, but when the flag is moved to the printing position F⁴ the disk 55 is released to thereby permit the key K on shaft 51 to make a partial rotation, and during this partial rotation the wheel 55 prevents movement of the flag F from the position F⁴ to the full line position F until the said disk 55 has fully completed half of 55 its cycle or rotary movement. At the end of this first half of the cycle of the disk 55 the flag F is released, however, to move to vacant position, and when the flag is in vacant position the disk 55 may then complete the remaining half of its cycle and

thus actuate the gear train including the gear 11 a second time.

Accordingly, the first half of the cycle of the disk 55, and consequently the shaft 51, actuates the gear train including the gear 11 to cause the printing mechanism to operate and take off the impression from the fare-type wheels. Then, after the impression is made by the release of the hammers 20 in the manner already explained, the travel of the disk 55 through the remaining half of its cycle, after the flag F has been returned to vacant position, simply actuates the gear train and connected mechanism to feed out the tape from the slot S of the cover of the printing unit as well as move the impression made on the tape during the first half of the cycle of the disk 55 out of the zone of the fare printing types. 25

Having described the operation and control of the disk 55, the means which enables the functions set forth to be carried out will now be described in detail:—

As shown in Figure 11 the disk 55 is 30 prevented from moving in a clock-wise direction by reason of the pawl 54 engaging the teeth 53 of the check disk on the shaft 51. Also, the said disk 55 is prevented from moving in a counter-clockwise direction by reason of the tooth 56 of the shiftable locking device D engaging in the notch 57. At a point directly opposite the notch 57 is a second notch 57^a which is intended to engage with the check tooth 56 at the end of half the cycle of rotation of the disk 55. 35

100 as will presently appear. Between the notches 57 and 57^a opening at the periphery of the disk 55, and also at diametrically opposite points on the latter, are suitable clearance notches 58 and 58^a.

105 For the purpose of shifting the locking device D the said disk 55 is also provided with the projecting lugs 59 and 59^a. That is to say, for the purpose of rocking the device D on its pivot d' against the tension of the spring d² to cause the check tooth 56 thereof to engage with either of the notches 57 or 57^a at the end of each half cycle of the disk 55, the said wheel carries the projections 59 and 59^a referred to. It will thus 110 be seen that the disk 55 of the printing unit actuating mechanism carries means for tripping the locking device D to cause the said disk to be locked in either its normal position or its half way position.

115 Referring now to the manner in which the flag constitutes a check upon the disk 55 to prevent its being driven through a full circle by the manipulation of the printing key, and also the means whereby the flag operates the locking device to remove the check tooth 56 from one of the notches 57 or 57^a, it will be observed from Figure 10 that the said flag F carries upon its shaft 60, journaled in the back 12 of the meter 120

130

casing, a series of instrumentalities for controlling its operation. One of these instrumentalities is the check disk 61 which directly cooperates with the disk 55 to permit 5 its operation when the flag is in printing position and its further operation when the flag is in vacant position, until the disk 55, through its own movement brings the locking device D again into play to cause the 10 check tooth 56 thereof to engage with the notch 57.

When the flag F is in the vacant position shown in Figure 11 the disk 55 is positioned so that the clearance notch 58^a there- 15 of will clear the entire periphery of the said check wheel 61 to permit the flag to move to either one of the positions F¹, F², F³ or F⁴ (see Figs. 11, 12, 13 and 14). And, when the flag is moved through said posi- 20 tions F¹, F² and F³ the periphery of the wheel 61 will register with the clearance notch 58^a to prevent movement of the wheel 55. At this point it may be conveniently noted that when the flag has reached the 25 first tariff position F¹ (Fig. 11) it has moved a sufficient distance to cause the stud 62 projecting from the face thereof to engage with the part 63 of the locking device D to shift it on its pivot d' and cause the 30 tooth 56 to withdraw from the notch 57. Thus the disk 55 which is normally en- gaged by the tooth 56 at the initial point of its cycle is released by the said tooth as soon as the flag moves to first tariff posi- 35 tion but is held against movement by the disk 61. The position of the locking device D after the flag has passed the position F¹ is such that the check tooth 56^a of the said locking device will bear against the smooth 40 periphery of the wheel 61 until the notch 64 is brought around in position to receive the tooth 56^a. This engagement of the tooth 56^a in the notch 64 does not take place until the flag reaches the printing 45 position F⁴ (Fig. 14), and by reason of this engagement the flag F can not be moved to vacant position, i. e. position F and it can not be moved back to not recording 50 position F³ due to the spring pressed pawl 55 engaging with the teeth of a ratchet wheel 66 also carried upon the flag shaft 60 (see Fig. 10).

The flag F is therefore held locked (Fig. 14) in printing position by the means above 55 referred to, and when locked in this position it will be seen that the check disk 55 of the printing unit actuating mechanism may be turned in a counter-clockwise direction, looking at Figure 14, until the pin 60 or projection 59^a on 55 has engaged with the portion 59^b of the locking device to rock the same on its pivot d' and withdraw the tooth 56^a from the notch 64 in the disk 61, and at the same time throw the tooth 66 56 against the periphery of the disk 55.

Upon a continued rotation of the latter through the key K, the said tooth 56 will drop into the notch 57^a and lock or stop rotation of the disk 55 (Fig. 15). As previously explained the rotation of the disk 55 for this distance operates the printing mechanism to take off the impression from the fare type wheels. 70

The shifting of the locking device as above described to cause the tooth 56 to engage 75 the notch 57^a releases the check disk 61, whereby the flag of the meter may be moved from printing position F⁴ to the full line vacant position shown in Figures 10 and 16. As the flag moves from printing position F⁴ (Fig. 15) to vacant position (Fig. 16) a stud 67 projecting from the face thereof trips the locking device D by engaging with the portion 63 thereof and brings the check tooth 56^a of the locking device into the notch 68 which prevents the flag F from being moved past vacant position until the printing key K has been moved through the remaining portion of its cycle of rotation to complete the actuation of the printing unit. 85 90

To permit the movement of the disk 55 to complete the printing operation, the check disk 61 is therefore provided with a clearance notch 69^a which clears the periphery of the disk 55. As the projection 59^a on the disk 55 passes the portion 59^b of the locking device it trips the same to throw the tooth 56^a out of engagement with the notch 68 and draw the tooth 56 against the periphery of the wheel 55 so that when the printing key completes the second half of its cycle the said tooth 56 will slip into the notch 57 and prevent further rotation of the said key. At the end of this operation which was permitted by the moving of the flag F from printing position to vacant position the said flag is released to move to either one of the tariff positions F¹ or F² to the not recording position F³, or printing position F⁴, and until the flag again reaches the 105 printing position F⁴ it operates as a complete check against the movement of the printing key K. 110

From the foregoing it will be apparent that the flag F constitutes a check upon the printing mechanism until the printing position F⁴ is reached, and while the printing mechanism is being caused to function to effect the printing, the flag F is locked against movement toward the vacant position, but when the printing has been accomplished, the flag is released to move to vacant position, and the printing mechanism is again locked against being manipulated to feed the paper or tape out of the slot S of the casing C as previously referred to. 115 120 125

In connection with the flag F it is pointed out that the same can be moved backward and forward between the positions F¹ and F³. When the flag is in either of the posi- 130

tions referred to it controls parts of the meter mechanism, which are of course suitably connected with the printing types, to enable the operator of the cab to operate the 5 meter in accordance with the conditions met during the trip. For instance when the flag is in position F^1 , or first tariff the meter mechanism including the fare types will be operated in accordance with the first tariff 10 rate, but if during the trip extra passengers are added the flag may be moved to the position F^2 or second tariff position. On the other hand if the machine should be disabled so that the passenger should not be charged for time and repairs or the like the flag F can be moved to position F^3 or not recording position. When the trip is resumed the operator may move his flag back to position F^2 or F^1 according to the conditions 15 then existing without in any way compelling the operation of the printing unit. All of the operations of the meter affected by the movement of the flag between any of the positions F^1 to F^3 are totaled up by 20 the mechanism in the printing types, and when the trip is over the printing unit then comes into play to take off the totals registered by the fare types.

In view of the description of the relation 30 and operation of the various units and cooperating instrumentalities it is thought that the features and advantages of the invention will be readily apparent, and it will of course be understood that changes in the 35 form, proportion and minor details of construction may be resorted to without departing from the spirit of the invention or scope of the appended claims.

I claim:

40 1. A printing unit for taximeters including in combination with fare type wheels, a plurality of normally restrained impression units, and means common to all of said impression units for progressively releasing said units for movement toward the type wheels and returning the same to restrained position.

2. A printing unit for taximeters including in combination with fare type wheels, a 50 plurality of normally restrained impression units, and cam means common to all of said impression units for progressively releasing said units for movement toward the type wheels and returning the same to restrained position.

3. A printing unit for taximeters including in combination with fare type wheels, a 55 plurality of normally restrained impression units, and a single cam shaft having cams for each of said impression units for progressively releasing said units for movement toward the type wheels and returning the same to restrained position.

4. A printing unit for taximeters including in combination with fare type wheels, a 60

plurality of spring-tensioned individual impression hammers, and a single actuating member common to all of said hammer units and having means for progressively releasing said hammers to engage with the type 70 wheels.

5. A printing unit for taximeters including in combination with fare type wheels, a plurality of individual impression hammers, and means for operating said hammers, said 75 means consisting of a shaft having a plurality of cams thereon, the valleys of said cams being progressively set circumferentially with reference to each other to progressively release the impression hammers toward the 80 type wheels.

6. A printing unit for taximeters including in the combination with the flag of the meter, fare-type wheels, and a plurality of individual impression units for the fare-type wheels, of cam means for progressively causing the operation of the impression units, a printing key operatively connected with the said cam means, and means for co-ordinating the movement of the flag and the 85 printing key.

7. A printing unit for taximeters including in the combination with the flag of the meter, fare-type wheels, and a plurality of individual impression units for the fare-type wheels, of cam means for controlling 90 the impression units, a shaft for operating said cam means, a printing key operatively connected with said shaft, means associated with the printing key for permitting the 95 operation of the flag through a portion of its cycle while said means remains locked until the flag reaches said point.

8. A printing mechanism for taximeters including the combination with the meter 100 casing and the type wheels located therein, of a printing unit detachably mounted in the casing above the type wheels in the casing, and means carried by the back of the meter for operating the printing mechanism and 105 a shaft carried by the printing unit and adapted to have a detachable engagement with an element of the operating mechanism.

9. A printing mechanism for taximeters including the combination with the meter 110 casing, of a printing unit detachably mounted in the casing above the type wheel position, means for operating the printing unit carried by one of the walls of the casing, and a member of the printing unit adapted to 115 detachably engage with the said operating means.

10. A printing mechanism for taximeters including in combination with the meter 120 casing, of a printing unit mounted in the casing above the type wheel position, means for operating the printing mechanism carried by one wall of the casing and including a gear having a hub portion provided with 125 a slot, and a shaft associated with the print- 130

ing unit and for means at one end for engaging in the said slot.

11. A printing unit for taximeters including, in combination with the meter casing, a platform adapted to be positioned in the casing over the type wheel position, impression mechanism, cam means for actuating the impression mechanism, paper feeding means including feed rolls operatively connected with the cam means, inked ribbon carrying rollers mounted at the under side of the platform, a main operating shaft mounted at one side of the unit and operatively connected with the cam means and also operatively connected with the inked ribbon carrying rollers.

12. A printing unit for taximeters including a platform adapted to be mounted above the type wheel position, arched guard plates carried by the platform and overlying the type wheel position, inked ribbon carrying rollers mounted at the under side of the platform and adapted to pull the inked ribbon over the guard plates, printing mechanism, paper feeding mechanism, and a single operating shaft for actuating the printing mechanism, and paper feeding mechanism, and inked ribbon supporting rollers.

13. A printing mechanism for taximeters including a printing unit, means for operating the unit including a printing key, a check disk movable with the key and having clearance notches in its periphery, a flag, a check disk movable with the flag and being adapted to move backward or forward in one of the notches of the disk of the printing key for approximately 180° of its cycle whereby the flag may be moved to any one of three positions while maintaining the check disk of the printing key locked, and a locking device adapted to be alternately actuated by one or the other of said check disks to lock the other.

14. A printing mechanism for taximeters including a printing unit, a printing key, a flag, a check disk associated with the key and having notches in its periphery, a check disk associated with the flag and having its periphery working in one of said notches for the major portion of the cycle of the flag whereby the flag may be moved backward or forward to different set positions while the check disk of the flag works free in said notch, a locking device for arresting the movement of the check disk of the flag at a point where the notch in said disk permits the check disk of the key to rotate, and means carried by the check disk of the key

for actuating the locking device to release the check disk of the flag to permit the latter to move to the end of its cycle.

15. A printing mechanism for taximeters including a printing unit, a printing key, a flag, a check disk associated with the flag, a check disk associated with the key and adapted to interlock with the flag disk whereby the flag may be moved backward or forward within a portion of its cycle while maintaining the key disk locked, a locking device adapted to engage with the flag disk to hold it stationary while the key disk turns to actuate the printing unit, means for causing the locking device to lock the key disk until the flag disk moves back to starting position, and means controlled by the flag disk for releasing the key disk to permit it to complete its cycle.

16. A printing unit for taximeters including in combination with fare type wheels, a plurality of impression hammers each having a resilient shank portion, a common carrying bar for the spring shanks of all the hammers, means for moving the bar to uniformly adjust all of the hammers radially and means for engaging with the ends of the hammers opposite the bar for controlling the movement thereof to and from the fare type wheels.

17. A printing unit for taximeters including in combination with fare type wheels, a plurality of resiliently mounted hammer elements arranged at one side of the type wheels, and a single operating unit having means for progressively releasing said resilient hammer units into operative engagement with the type wheels and returning the same to normal position.

18. A printing unit for taximeters including in combination with the meter casing and type wheels arranged in a fixed location therein, an actuating member carried by the casing for actuating the printing unit, and said unit including a hood detachably engaging with the meter casing, impression mechanism carried by the hood, means also carried by the hood for operating the impression mechanism, and a member of said means adapted to detachably and operatively engage with said actuating member carried by the meter casing.

In testimony whereof I hereunto affix my signature in the presence of two witnesses.

JULIUS GLUCK.

Witnesses:

A. DUCASSE,
B. C. PALMER.
